DESIGN FOR A HANDBAG

Maurice J. Kruger, New York, and Sanford B. Megdall, Brooklyn, N. Y.; said Kruger assignor to Kruger-Ressler, Inc., New York, N. Y., a corporation of New York, and said Megdall assignor to Fulton Frame Mfg. Co., New York, N. Y., a copartnership

Application June 3, 1947, Serial No. 139,430

Term of patent 3½ years

(Cl. D87—3)

To all whom it may concern:

Be it known that we, Maurice J. Kruger and Sanford B. Megdall, both citizens of the United States, residing respectively in New York city, county and State of New York; and Brooklyn, in the county of Kings and State of New York, have invented a new, original, and ornamental Design for a Handbag, of which the following is a specification, reference being had to the accompanying drawing, forming part thereof.

In the drawing:

Fig. 1 is a front elevational view of a handbag, showing my new design;

Fig. 2 is a side elevational view thereof;

Fig. 3 is a top plan view showing the cover section swung away from the other sections;

Fig. 4 is a view similar to Fig. 1, showing the cover member in inverted open position;

Fig. 5 is a view similar to Fig. 2, showing the base section swung away from the other sections; and

We claim:

The ornamental design for a handbag, substantially as shown.

MAURICE J. KRUGER.
SANFORD B. MEGDALL.
